UNITED STATES PATENT OFFICE

117,837

DESIGN FOR A CYLINDER TYPE VACUUM CLEANER CABINET

Homer S. Tuttle, Weedsport, N. Y.

Application October 11, 1938, Serial No. 80,360

Term of patent 3½ years

To all whom it may concern:

Be it known that I, Homer S. Tuttle, a citizen of the United States, residing at Weedsport, in the county of Cayuga and State of New York, and having my post-office address at Maple Park, Weedsport, New York, have invented a new, original, and ornamental Design for a Cylinder Type Vacuum Cleaner Cabinet, of which the following is a specification, reference being had to the accompanying drawing, forming part thereof.

Fig. 1 is a front perspective view of the cylinder

type vacuum cleaner cabinet showing my new design in a closed position; and

Fig. 2 is a front perspective view of the same in open position.

The back and end, not shown in Figures 1 and 2, present substantially the same appearance as the front and end views shown in Figures 1 and 2.

I claim:

The ornamental design for a cylinder type vacuum cleaner cabinet, substantially as shown and described.

HOMER S. TUTTLE.
